[57] **CLAIM**

The ornamental design for an electronics cabinet fold-up computer storage tray, as shown and described.

DESCRIPTION

FIG. 1 is a front perspective view of the electronics cabinet fold-up computer storage tray according to the present invention, the broken line drawing of electrical cables is for illustrative purposes only and forms no part of the claimed design;

FIG. 2 is a side view of the electronics cabinet fold-up computer storage tray of FIG. 1;

FIG. 3 is a top view of the electronics cabinet fold-up computer storage tray according to the present invention;

FIG. 4 is a back view of the electronics cabinet fold-up computer storage tray according to the present invention;

FIG. 5 is a front view of the electronics cabinet fold-up computer storage tray of the present invention;

FIG. 6 is a bottom view of the electronics cabinet fold-up computer storage tray of the present invention;

FIG. 7 is an opposite side view of the electronics cabinet fold-up computer storage tray of the present invention, the broken line drawings of a portion of the inside of the electronics cabinet door and the computer on the tray are shown for illustrative purposes only and form no part of the claimed design; and,

FIG. 8 is an opposite side view of the electronics cabinet fold-up computer storage tray of the present invention, the tray is shown in folded-down position, the broken line drawings of the inside of the electronics cabinet door and a computer on the tray are shown for illustrative purposes only and form no part of the claimed design.
